UNITED STATES PATENT OFFICE.

HARRY T. ANDERSON, OF BUTLER, PENNSYLVANIA, ASSIGNOR TO HARRY VISSERING & COMPANY, OF CHICAGO, ILLINOIS, A CORPORATION OF ILLINOIS.

UNCOUPLING DEVICE FOR COUPLINGS.

1,189,773.

Specification of Letters Patent. Patented July 4, 1916.

Application filed March 5, 1913. Serial No. 752,200.

To all whom it may concern:

Be it known that I, HARRY T. ANDERSON, a citizen of the United States, and a resident of Butler, in the county of Butler and State 5 of Pennsylvania, have invented certain new and useful Improvements in Uncoupling Devices for Couplings, of which the following is a specification.

My present invention relates to devices for 10 operating the locks of couplers used in railway rolling stock and more particularly to improvements in the uncoupling levers commonly used in connection with automatic and other car couplers, and has special reference to the provision of an improved type 15 of that class of uncoupler device which is operable from the side of the car or other structure to which it is applied.

The principal objects of my present invention are the provision of an improved device characterized as above which will 20 readily accommodate itself to coupler pins of different locations relatively to the mounting of operating lever, and a device 25 so characterized which is thus accommodative both longitudinally and laterally to various locations of the pin and likewise accommodative to the movement of the draw bar as well longitudinally and laterally; the provision 30 of an improved type of connecting link device employing reciprocable members which permit the operating lever to be presented at all times in substantially the same operating position; the provision of an improved 35 device wherein the operating lever and the cooperating connecting link device are separable or otherwise disengageable to the end, first, that should either part become broken or so extensively bent in service that 40 the replacement of either part is required, the discarding of the entire lock operating device will not be necessitated, and, second, one wherein the connecting link device may be used with other types of operating levers 45 already applied to cars without requiring the demounting or discarding of an entire lock operating device in order to utilize and gain the advantages of my present improvements; the provision of an improved connecting link device which may be most readily applied to coupling levers for their repair and equally readily detachable, and one which will not, however, tend to become accidentally detached in service; together

with such additional objects as may be hereinbelow disclosed.

In the attainment of the objects above mentioned and in gaining certain further benefits which will hereinafter appear, I have provided the construction illustrated in the accompanying drawings, wherein—

Figure 1 is an end view of a portion of a car body having one embodiment of my improved device applied thereto; Fig. 2 is a side elevational view of the device of Fig. 1, 65 showing the coupler in locked position; Fig. 3 is a view similar to Fig. 2 showing the coupler in "lock-set" position; Figs. 4 and 5 are enlarged detail views of the connecting link device employed in connection with the 70 device of Figs. 1 and 2, in the positions there shown, Fig. 4 being partly in section. Fig. 6 is a view partly in section taken on the line VI—VI of Fig. 5; Figs. 7 and 8 are views 75 similar to Figs. 4 and 5 illustrative of a modified form of construction; Fig. 9 is an enlarged view of a detail of the construction of the device of Figs. 7 and 8; and Figs. 10 and 11, and 12 and 13, are pairs of figures 80 similar to Figs. 4 and 5 illustrative of further modified forms of construction.

Referring first to Figs. 1 and 2, it will be noted that I have here illustrated my invention as embodied in a device for the operating of the locking pin 10 of a coupler head 85 11, supported as here shown by a bracket 12 from the buffer 13 of a car body 14. The uncoupling device itself comprises an operating lever 15, supported from any convenient location, such as the end sill, by 90 means of suitable brackets 16, 16^a, and a connecting member here illustrated as a vertically disposed lifting link device, 17, more fully hereinafter described, the operating lever 15 having a handle 15^a and the connecting link device 17 having engagement 95 with the pin 10 as indicated at 18, where it passes through the enlarged eye thereof.

As will be most clearly seen upon inspection of Fig. 2, the lever 15 is formed with 100 an operating rocker arm portion 19 which is arranged to clear the buffer or dead wood 13 and the rocker arm 19 is extended forward materially to the end that the coupler head 13 may freely move laterally without tendency 105 to place undue strain upon the device or to range the same through such strain.

Though obviously other forms of sup-

porting brackets 16—16^a may be used for maintaining the operating lever in position, I preferably employ the device illustrated perhaps most clearly in Fig. 2, wherein it will be observed that the support here shown comprising two portions, of which the body or base portion 20 may be permanently attached to the car by screws 21—21, passing through the holes 21^a—21^b, the member 20 having a tongued portion 22 adapted to make dove-tailed connection with the removable cap portion 23 which is apertured at 24 for the passage of the lever 15 therethrough, holes 25—25, and 26 being provided in the members 22 and 23, respectively, to the end that when they are assembled in such a manner that such holes register the base and cap will be prevented from movement by the insertion of a cotter pin 27 therethrough.

In order to provide a simpler and more efficient connection between the members 15 and 17, to the end that my improved device may be applied without alteration to cars of various design, irrespective of the location of the pin 10 relatively to a convenient mounting for the member 15 and also to provide for a ready replacement of the member 17 should it become broken or irreparably distorted in service, as well as to provide a design of connecting link which may be used in connection with other types of coupler operating levers employed in railroad service at this day, I provide at the end of the off-set portion 19 of the lever 15, means for engaging the connecting link 17 here shown as a closed eye 31, which should preferably be sufficiently large to allow the connecting link device 17, now to be described, to be readily attached thereto.

Referring now more particularly to the link device of Figs. 4 and 5 it will be observed that to the end that when the operating handle 15^a is moved to the right of its position shown in Fig. 2, lifting the pin 10 to the "lock-set" position shown in Fig. 3, and allowing the handle 15^a thus to fall back to the position shown in Fig. 3, I employ in the link device 17 a pair of co-operating reciprocable members 32 and 33 respectively provided with eyes 34 and 35, whereby mutual engagement is attained and reciprocable movement is possible. The members 32 and 33 may be of malleable iron cast in the customary manner in the operative relation shown, or they may be forgings in case extraordinary strength is required.

For the purpose of making engagement between the lower end of the member 32 and the eye 18 of the pin 10, the member 32 is provided with a normally open eye forming a hook 36, the outer end thereof 37 being carried beyond the upper portion 38 of

the eye 18 of the pin 10, and spaced apart 65 from the adjacent portion 39 of the hook as is clearly to be seen on inspection of Fig. 5.

For effecting connection between the upper end of the member 33 and the portion 19 of the member 15, I provide on the upper part of the member 33 a yoke 40 apertured at 41—41 and having a housing 42 open at one end 43 and apertured at 44 for the reception of one leg 46 of a U-shaped latching member 47, the opposite leg thereof passing 75 through the apertures 41—41 and through the eye 31 on the member 19. For holding the latch 47 in adjusted position, and thereby locking the members 15 and 17 together, I mount within the housing 42 and around the leg 46, a coiled spring 48, holding it in position by means of a washer 49, riveted in position on the end of the leg 46 as indicated at 50.

Referring now to the device of Figs. 7, 85 8 and 9, it will be observed in this embodiment of my present improved reciprocable link device, the eye 31 is supported upon a post 47^a formed integrally upon the member 33^a and held in position thereupon by 90 means of a strap 51 apertured at 52 (Fig. 9) for engagement with the member 33^a and bifurcated as indicated at 52—52 to the end that it may straddle the post 47^a, the member 51 being preferably formed of 95 malleable metal so that the extremities 53—53 of the bifurcated portions 52^a—52^b may be given a quarter bend in order to bear against the eye 31 so that the member 51 may be prevented from disengagement 100 therefrom.

In the device of Figs. 10 and 11 connection is made between the member 33^b and the eye 31 by forming at the upper part of the member 33^b a bifurcation 40^b—40^b apertured at 41^b—41^b and provided with a housing 42^b, wherein I mount a plunger latch 47^b against the head of which a spring 48^b bears, such spring being held in position by means of a washer 49^b which is retained in 110 position by riveting thereover the margin of the housing 42^b as indicated at 50^b. In the device of Figs. 12 and 13, however, the member 33^c is provided with a plain eye 47^c for engagement with the eye 31 of the 115 portion 19 of the operating lever 15, the present form of device being somewhat less expensive to manufacture than those above described and being conveniently employed in equipping new rolling stock, or where the 120 use of a separable or detachable reciprocating link device 17 is not required.

In the employment of the device of Figs. 12 and 13 it is highly desirable to use detachable brackets such as are described in 125 connection with Figs. 1 and 2, since the hook 36 has first to be applied to the eye 18 of the pin 10, the lever 15 then moved to

operating position and the bracket members 23 applied to the members 20 and pinned in position thereupon.

It is believed that the operation of devices employing my invention will be understood by those skilled in the art to which it pertains without more exemplified description.

Having thus described my invention and illustrated its use, what I claim as new and desire to secure by Letters Patent is the following:

1. The combination with a coupler having a locking device and a lever for operating said locking device, of a longitudinally freely movable reciprocable connection between said lever and locking device, comprising a pair of members each provided adjacent one end with an eye engaging the other of said members.

2. An uncoupling device for coupler locks comprising, in combination, an operating lever, a coupler pin, a link therebetween including two members connected together non-rotatively and within fixed limits freely movable longitudinally rela-

tively to each other, a pin mounted on and slidable relatively to one of said members adapted to connect said member to said operating lever and a spring adapted to yieldingly retain said pin in engagement with said operating lever.

3. An uncoupling device for coupler locks comprising, in combination, an operating lever, a link including two members connected together non-rotatively but freely movable longitudinally relatively to each other, means permanently connected to one of said members for releasably connecting said link with the coupler lock, a pin mounted on and slidable relatively to one of said members adapted to connect said member to said operating lever and a spring adapted to yieldingly retain said pin in engagement with said operating lever.

In testimony whereof I have hereunto signed my name in the presence of the two subscribed witnesses.

HARRY T. ANDERSON.
